UNITED STATES PATENT OFFICE

163,954

DASHBOARD TRAY

Seymour Kulwin, Chicago, Ill.

Application July 29, 1950, Serial No. 11,475

Term of patent 14 years

(CL. D14—6)

To all whom it may concern:

Be it known that I, Seymour Kulwin, a citizen of the United States, residing at Chicago, in the county of Cook and State of Illinois, have invented a new, original, and ornamental Design for a Dashboard Tray, of which the following is a specification, reference being had to the accompanying drawings, forming a part thereof, in which:

Fig. 1 is a top plan view of a dashboard tray;
Fig. 2 is a front elevation thereof;
Fig. 3 is a bottom plan view thereof; and
Fig. 4 is an end elevation viewing Fig. 2 from the left.

I claim:

The ornamental design for a dashboard tray, as shown.

SEYMONR KULWIN.
